UNITED STATES PATENT OFFICE

EDWARD E. SULLIVAN, OF FALL RIVER, MASSACHUSETTS

WINDOW SHADE AND CURTAIN FIXTURE

Application filed July 23, 1931. Serial No. 552,753.

The invention relates to a window shade and curtain fixture and more especially to an adjustable window shade and curtain bracket.

5 The primary object of the invention is the provision of an article of this kind wherein a window shade can be hung upon a window and also a curtain pole supported in association therewith, the article being of novel 10 form and readily adjustable to fit varying widths of window frames, while requiring but a single fastener to secure the hangings in place and likewise the article to the window frame.

15 Another object of the invention is the provision of a fixture of this character, whereby a curtain pole will be properly supported in relation to a window shade, so that on raising and lowering the latter it will not interfere 20 with the curtains when hung from the pole, the major portion of the fixture being made from a single piece of sheet material, preferably metal.

25 A further object of the invention is the provision of a fixture of this character, which is extremely simple in construction, thoroughly reliable and efficient in its purposes, strong, durable, neat and attractive in appearance, assuring the proper hang to the 30 window shade and curtains, which latter may be supported from a pole or rod, and inexpensive to manufacture.

With these and other objects in view the invention consists in the features of construction, combination and arrangement of parts as will be hereinafter more fully described, illustrated in the accompanying drawing, which discloses the preferred embodiment of the invention, and pointed out 40 in the claims hereunto appended.

In the accompanying drawing:—

Figure 1 is a perspective view of the fixture constructed in accordance with the invention and applied to a window frame.

45 Figure 2 is a side view, the same being partly in section.

Figure 3 is a perspective view of the fixture detached from the window frame with 50 the shade bracket removed.

Figure 4 is a detail sectional view through the rod socket member.

Similar reference characters indicate corresponding parts throughout the several views in the drawing.

55 Referring to the drawing in detail, the fixture comprises a base strip 10 with a tapered lower end 11 and the upper end portion is formed with a right angular bend 12 having a pointed downturned nib 13, while the lower 60 end is provided with a hole 14 so that through the instrumentalities of this nib 13 and a fastener engaged in the hole 14 the base strip 10 can be secured in a selected locality on the 65 head of a window frame A for the mounting of the fixture.

Projecting laterally from the base strip 10 at the outer longer edge of the same near its top portion is an ear 15 carrying a tubular socket member or sleeve 16 in which is adapted 70 to be received one end of an arched curtain rod (not shown) for the fastening of the latter to the fixture.

75 Suitably fastened to and carried by the base strip 10 near its lower end is a window shade bracket 17 for the trunnion end of a shade roller, the bracket being of the conventional form.

80 Integrally formed with the base strip 10 and projecting from its edge having the ear 15 but spaced below the same is a combined curtain pole and rod holder B, this including the short connecting web 18, the upper arm 19 having therein the curtain rod seat or notch 20, and pole seat or notch 21, respectively. 85 Engaged in the crotch 22 of the bight 23 between said seats is the free end 24 of an upwardly curved brace 25, which end contacts only at this point with the arm, the brace being formed with the web 18 at its 90 lower portion and the same is engaged in the manner stated with said arm 19 firmly holding the same so that it will not sag under a load in supporting the pole and rod with 95 hangings thereon.

The outer free end of the arm 19 is formed with a slot 26 the same being vertically directed and in which is received a fastener 27 of an ornament 28 which gives a finished 100

appearance to the fixture and lends attractiveness thereto as well as ornamentality.

It is of course understood that there is employed a right and left hand fixture for the mounting of the window shade, curtain pole and rods or in other words there is a pair to a set for each window.

The fixture is preferably made from sheet metal, cut, stamped or otherwise formed in its manufacture and also to give strength and durability thereto, although it may be otherwise made and constructed from any suitable material or materials, its shape and size as well as the material or materials from which it is made being no part of the present invention.

It is also to be understood that changes, variations and modifications may be made in the invention without departing from the spirit of the same or sacrificing any of its advantages and as fall properly within the scope of the claims hereunto appended.

What is claimed is:

1. A fixture of the kind described, comprising a strip-like base having an ear projected laterally therefrom, a rod socket member on the rear, a window shade bracket on the base, a web on the base, an arm extending forwardly from the web to one side of the base and having curtain pole and rod seats, and a brace forming a part of the web and having its free end contacting with the arm between the seats.

2. A fixture of the kind described, comprising a base strip having an ear projected laterally therefrom at one edge of the same, a rod socket member on the ear, a window shade bracket on the strip, an arm integral with and extending forwardly from the strip at one edge of the same and having spaced curtain pole and rod seats therein, and a brace formed with the strip and disposed below the arm and curved upwardly into contact with said arm at the free edge of said brace.

3. A fixture of the kind described, comprising a base strip having an ear projected laterally from one edge of the same, a rod socket member on the ear, a window shade bracket on the strip, an arm integral with and extending forwardly from the strip, at one edge of the same, and having spaced curtain pole and rod seats therein, a brace formed with the strip and disposed below the arm and curved upwardly into contact at its free end with said arm, a fastener receiving lower end formed on the strip, and a pointed fastener nib at the upper end of the strip and inset therefrom.

60 In testimony whereof, I affix my signature.
EDWARD E. SULLIVAN.
